UNITED STATES PATENT OFFICE

WILLIAM SCHROEDER, OF ORANGE, NEW JERSEY, ASSIGNOR TO WESTERN ELECTRIC COMPANY, INCORPORATED, OF NEW YORK, N. Y., A CORPORATION OF NEW YORK

LIFTING DEVICE

Application filed January 11, 1930. Serial No. 420,065.

This invention relates to lifting devices, and more particularly to a lifting device or grapple for cylindrical objects, such as cable reels.

5 An object of the present invention is to provide a lifting device of simple and durable construction, and which may be safely and expeditiously manipulated for lifting and moving objects of various sizes.

10 One embodiment of the invention contemplates the provision of a lifting device or grapple for handling cable reels, wherein a motor driven worm within a casing actuates a gear for rotating the entire grapple

15 if free, or if prevented from rotation by the reel being handled, the gear operates a member threaded in a sleeve having a cone-shaped friction surface for causing a pair of arms to engage the ends of the reel. A

20 pair of horizontal members are slidable vertically upon the arms and serve to center the grapple with respect to the reel, and thereafter prevent displacement of the reel.

25 Limit switches in the motor circuit and included in the arms of the yoke connected with the usual cable for preventing undue rotation of the casing around its vertical axis respond when abnormal conditions are encountered to prevent further rotation in

30 one direction while permitting rotation in the reverse direction.

These and other features and advantages of the invention will become apparent from the following detailed description, reference being had to the accompanying drawings, wherein

35 Figs. 1 and 2 are front and side elevational views, respectively, of a grapple embodying features of the invention;

40 Fig. 3 is a plan view thereof;

Fig. 4 is an enlarged fragmentary sectional view on line 4—4 of Fig. 2;

Fig. 5 is an enlarged fragmentary plan sectional view on line 5—5 of Fig. 1, and

45 Fig. 6 illustrates, diagrammatically, a preferred form of an electrical operating circuit for the improved grapple.

Referring now to the drawings, wherein like reference numerals designate corresponding parts throughout the several views,

it will be observed that a casing or framework is indicated generally by the numeral 10 and comprises upper and lower halves 11 and 12, respectively. Rotatably journalled in the casing 10 is a vertical hollow 55 shaft 14 which projects through the bottom of the casing and terminates in a frustoconical portion 15, upon which is rotatably suspended a yoke member 16. The yoke member 16 terminates in a bifurcated portion for pivotally supporting oppositely disposed angular gripping members 20—20, each comprising a short horizontal arm 21 and a relatively long vertical arm 22. It will be observed that the horizontal arms are 60 pivoted between their ends in the bifurcated extremities of the yoke. A vertical screw member 24 is threaded in the hollow shaft or sleeve 14 and is axially movable therein upon the rotation of the shaft with respect 65 to the member. The member 24 projects beyond the lower side of the casing as well as shaft 14 and is formed with an enlarged head portion 25 for pivotally interconnecting with the extremities of the arms 21. 70 Within the casing, a gear 26 is keyed or otherwise secured to the sleeve 14, the sleeve and gear being supported upon ball bearings 27 resting upon a portion of the exterior wall of the casing. The gear is connected 75 by means of reducing gear 29 with a worm 30 secured upon and rotated by a horizontal shaft 31 suitably supported in ball bearings and having one end projecting from the casing for attachment through a suitable 80 coupling 32 to a shaft 33 of an electrical motor 34 mounted upon the exterior of the casing. Thus, when the motor is started, the gear 26 is rotated causing a corresponding 85 rotation of the sleeve 14.

90 Each arm 22 has suitably secured thereto at the lower end thereof, a pair of angularly disposed extensions 37 terminating in inwardly projecting portions 38 for engaging the underside of the periphery of the article to be lifted, such as a shipping reel of cable or wire 40. Horizontal bracket members 42 are mounted upon the arms 22 so that they are free to slide upwardly or downwardly when maintained in the hori- 95 100

zontal plane. The ends of the brackets are provided with apertures through which rods or tubes 43 are past to interconnect the corresponding ends of the bracket members. 5 Sufficient clearance is provided in the brackets so that the rods are freely slideable there-through as well as rotatable therein, thus permitting a free relative movement of the rods through the arms 22 during the opening and closing thereof. The ends of the rods are flanged to prevent the displacement thereof from the bracket members.

An eye or loop member 47 is pivoted to the casing 10 for supporting the entire cable 15 or lifting device from a hook 48 suspended through the usual cable or tackle of any suitable hoisting crane of the cantilever arm type, not shown in detail since it is unnecessary to a complete understanding of the 20 invention.

For convenience, the improved grapple is preferably constructed so that it may be rotated either in a clockwise or a counter-clockwise direction. In the present embodiment of the invention, the direction of rotation of the grapple is reversed by reversing the direction of rotation of the operating motor 34. For this reason, the motor 34 is series wound and operated by direct current 25 from a battery 44 (Fig. 6) or other suitable source. A reversible switch 45 is provided in the operating circuit of the motor for reversing the direction of the current flow in the field winding 46 of the motor 34 to 30 reverse the direction of rotation of the motor and thereby the grapple.

Means is provided for automatically opening the motor operating circuit upon a predetermined abnormal strain during the rotation 40 of the grapple in either direction. The usual guide wire 50, familiarly known as the "tag line" of the crane, extends over a pulley 51 on the arm 52 of the crane and terminates in a yoke or bifurcated portion 45 53, the extremities of which are pivotally attached to operating rods 54—54 of limit switches 55 and 56 rigidly secured to the exterior of casing 10 on opposite sides thereof (Figs. 3 and 5). Each limit switch 50 consists of a fixed contact member 57 and a movable contact member 58 carried by the operating rod 54, the contacts being maintained in a closed condition normally due to the effect of a coil spring 59 surrounding the 55 rod 54. When an abnormal strain is placed upon either of the arms of the yoke 53, the rod 54 of the associated switch is arranged to thereby open the contact members thereof although the corresponding members of the 60 other switch are maintained closed.

Referring to Fig. 6, it will be noted that when contact terminals 60 and 61 of the reversing switch 45 are closed, an electrical operating circuit of the motor is completed 65 which may be traced as follows: from the

battery 44, through motor armature 34, switch terminal 60, switch 45, motor field winding 46 in the direction indicated by the arrow 62, switch 45, switch terminal 61, and contacts 57 and 58 of limit switch 55 to battery. The grapple may now be rotated by the motor in a clockwise direction. When an abnormal strain is encountered during such rotation, the contacts of the limit switch 55 are opened, thereby opening the electrical operating circuit of the motor and thus preventing further rotation of the grapple in a clockwise direction. However, by opening the contact terminals 60 and 61 of the reversing switch 45 and closing contact terminals 63 and 64 thereof, the motor may be operated to rotate the grapple in a counter-clockwise direction. In this instance, the electrical operating circuit of the motor may be traced as follows: from the battery 44, through motor armature 34, switch terminal 60, switch terminal 64, switch 45, motor field winding 46 in the direction indicated by the arrow 65, switch 45, switch terminal 63, and contacts 57 and 58 of limit switch 56 to battery. The limit switch 56 operates as described above in connection with the limit switch 55 to open the motor operating circuit when an abnormal strain is encountered during the rotation of the grapple in a counter-clockwise direction.

It is to be understood that the embodiment of the invention herein illustrated and described is merely a convenient and useful form of the invention which is capable of other applications within the scope of the appended claims.

What is claimed is:—

1. In an article lifting device, a suspended framework, a pair of opposing arms pivoted thereon and terminating in article engaging elements, means for causing a relative movement of the arms to engage the elements with the periphery of the article at a plurality of points below the center of gravity thereof, and a plurality of members interconnecting and freely slideable upon the arms for engaging the upper portion of the periphery of the article to prevent its displacement from the elements.

2. In an article lifting device, a suspended framework, a plurality of article engaging arms secured thereto, means for rotating the arms as a unit in a constant relative relationship around a vertical axis, and means responsive to the engagement of the arms with a fixedly positioned article to convert the rotating movement of the arms into a relative movement thereof to cause the arms to support the article.

3. In an article lifting device, a casing, a motor mounted thereon, a shaft driven thereby and having a worm within the casing, a worm gear within the casing meshing with the worm, a vertical sleeve also in the

casing rotated by the gear and having an internally threaded portion, a member threaded thereinto, a head carried thereby, and a plurality of arms pivotally attached 5 to the casing and the head and actuated by a longitudinal movement of the member caused by the rotation of the sleeve.

4. In an article lifting device, a suspended framework, a vertical sleeve carried thereby 10 having a conical exterior surface at the lower end thereof, means for rotating the sleeve, a spider frame surrounding the sleeve and having a conical surface cooperating with the first mentioned conical surface to 15 support and provide a friction drive for rotating the spider in response to the rotation of the sleeve, and means secured to the spider for supporting an article.

5. In an article lifting device, a suspended 20 framework, means terminating in a bifurcated yoke for preventing the rotation of the framework about the vertical axis thereof, relative movable article engaging means supported by the framework, means for 25 causing a relative movement thereof to engage an article, means for rotating the article in either direction independently of the framework, and means in the yoke responsive to a predetermined opposing 30 force in the rotation of the article in a direction to prevent the further rotation thereof in that direction while permitting the rotation thereof in the reverse direction.

6. In an article lifting device, a framework, suspending means therefor, means 35 for preventing the rotation of the framework about the vertical axis of the suspending means, article supporting means carried by the framework, an electrical motor for 40 rotating the supported article in either direction independently of the framework, an electrical circuit therefor, and means in the circuit responsive to a predetermined force for preventing rotation of the article in one 45 direction while permitting the rotation thereof in the reverse direction.

7. In a device for lifting a cylindrical article, a suspended framework, a pair of arms secured thereto and terminating in portions 50 for engaging the lower portion of the periphery thereof and supporting an article, a horizontal member freely slideable upon each arm and extending on each side thereof, and a freely horizontal cylindrical member inter- 55 connecting the opposing ends of the horizontal members for engaging the upper portion of the article at spaced points to prevent a displacement of the article from the pair of arms.

8. In an article lifting device, a framework, a pair of opposing arms pivoted thereon, each terminating in article engaging elements, means slidably carried by the arms for centering them upon an article and means for causing a relative movement of

the arms to engage and thereby support an article.

9. In an article lifting device, a plurality of article engaging members, means for rotating the members as a unit in constant relative relationship, and means responsive to the engagement of one of the members with a fixedly positioned article for converting the rotating movement of the members into a relative movement thereof to cause the 70 members to firmly grip the article. 75

10. In an article lifting device, a framework, a member rotatably carried thereby having a conical exterior surface, means for rotating the member, a frame having a 80 conical surface cooperating with the first conical surface to support and provide a friction drive for rotating the frame through the rotation of the member, and means carried by the frame for supporting an article. 85

11. In an article lifting device, a framework, article supporting means carried by the framework, means for rotating the supported article independently of the framework, and means responsive to a predetermined opposing force encountered in the rotation of the article for preventing further rotation thereof. 90

12. In an article lifting device, a framework, article supporting means carried by the framework, an electrical motor for rotating the supported article independently of the framework, an electrical circuit therefor, and means responsive to a predetermined opposing force encountered in the rotation of the article for opening the circuit to stop the motor. 95

13. In an article lifting device, a framework, article supporting means carried by the framework, means including an electrical motor and an operating circuit therefor for rotating the supported article in either of a plurality of directions independently of the framework, and means including a plurality of limit switches connected in the motor operating circuit and responsive to a predetermined opposing force encountered in the rotation of the article in one of said directions for preventing further rotation of the article in that direction while permitting the rotation of the article in another of said directions. 110 115

In witness whereof, I hereunto subscribe my name this 27th day of December A. D., 1929. 120

WILLIAM SCHROEDER.
